UNITED STATES PATENT OFFICE.

PAUL W. BEECH, OF MEMPHIS, TENNESSEE, ASSIGNOR OF TWO-THIRDS TO
WILLIAM K. BURTON AND THOMAS L. JONES, OF SAME PLACE.

HOT-AIR FURNACE.

SPECIFICATION forming part of Letters Patent No. 672,845, dated April 23, 1901.

Application filed February 2, 1900. Serial No. 3,736. (No model.)

To all whom it may concern:

Be it known that I, PAUL W. BEECH, a citizen of the United States, residing at Memphis, in the county of Shelby and State of Tennessee, have invented certain new and useful Improvements in Hot-Air Furnaces, of which the following is a specification.

My invention relates to hot-air furnaces; and its primary object is to provide a furnace so constructed as to secure the maximum radiation of heat from the fuel employed.

Further objects of the invention are to prevent cracking or buckling of the shell or casing of the furnace caused by expansion and contraction, to construct the shell or casing of a furnace in sections to facilitate its being set up for use, said sections being so connected as to be thoroughly dust-proof and gas-proof, to provide means for affording a direct draft for starting the fire, and generally to so improve the construction of furnaces of the class above named as to increase their durability and heating capacity.

An important characteristic of the invention is the employment of supplemental radiator-chambers arranged at the sides and rear of the main combustion-chamber to afford a greatly-increased radiating-space for the flame and products of combustion and to effect a more thorough combustion of the gases.

The construction of the improved furnace will be fully described hereinafter and defined in the appended claims in connection with the accompanying drawings, which form a part of this specification, and in which—

Figure 1 is a rear elevation of a furnace embodying the invention. Fig. 2 is a side elevation of the same, partly in section. Fig. 3 is a front elevation of the furnace. Fig. 4 is a vertical longitudinal section on the line 4 4 of Fig. 5. Fig. 5 is a transverse vertical section on the line 5 5 of Fig. 2. Fig. 6 is a longitudinal vertical section on the line 6 6 of Fig. 1. Fig. 7 is a transverse vertical section on the line 7 7 of Fig. 2. Fig. 8 is a longitudinal section of a modified construction of the furnace. Fig. 9 is a transverse vertical section on the line 9 9 of Fig. 8. Fig. 10 is a longitudinal vertical section on the line 10 10 of Fig. 9; and Fig. 11 is a side eleva-

tion, partly in section, of the modified construction shown in Figs. 8, 9, and 10.

In the construction shown in Figs. 1 to 7, inclusive, the reference-numeral 1 designates the bottom plate of the furnace, provided on its under side with transverse ribs 2, consisting of angle-irons riveted to the bottom plate. The shell or casing of the furnace consists of an upper dome-shaped section 3 and a lower section 4, the latter being beveled outward at its opposite sides and rear end, as shown at 5, 6, and 7, to form combustion ducts or passages along the sides and back of the furnace. The meeting edges of the two sections 3 and 4 are securely connected by means of oppositely-disposed angle-bars 8 and 9. The vertical flanges of these angle-bars are riveted to the sections, and the horizontal flanges thereof are firmly bolted together, as clearly shown in the drawings. The joints between the edges of the sections may be suitably packed with fireproof packing to effectually prevent the escape of gases.

10 and 11 designate the auxiliary side combustion or radiator chambers, which are of oval form in cross-section and extend from the front wall of the shell or casing to a point beyond the rear wall thereof. These auxiliary side radiators are secured to and communicate with the lower section 4 of the casing by means of elbow-pipes, each comprising two sections 12 and 13, formed with anular flanges 14, secured together by bolts 15. The lower ends of the elbow-sections 12 are formed with flanges 16, which are bolted to the beveled sides 5 and 6 of the lower section of the casing.

17 designates a rear auxiliary radiator, which may be of any suitable construction, but preferably of polygonal shape, and is connected by an elbow-pipe connection 18 to the rear beveled portion 7 of the casing. The ends of the elbow 18 are formed with flanges 19 and 20, the flange 19 being bolted to the beveled end portion 7 and the flange 20 secured to a depending squared collar 21 by angle-bars 22, bolted to the collar 21 and flange 20. The rear radiator 17 communicates with the side radiators by means of telescoping flanged pipes 23 and 24, bolted, respectively, to the inner sides of the radiators 10 and 11 and the opposite sides of the rear radiator and

secured together by suitable bolts 25. As shown in Fig. 7, the side radiators are supported by brackets 26 and 27, projecting from opposite sides of the furnace shell or casing, the upper ends 28 of said brackets being hollowed out to conform to the oval contour of the radiators.

29 designates the front of the furnace, formed at about its center with a fuel-opening 30, communicating by means of a passage 31 with the fire-box of the furnace. Below the fuel-opening 30 is an opening 32, communicating by a passage 33 with the interior of the fire-box, and below the opening 32, near the lower edge of the front 29, is an opening 34, communicating by a passage 35 with the ash-pit of the furnace.

36 and 37 designate openings in the furnace-front, on opposite sides thereof, communicating by pipes 38 with the interior of the side radiators 10 and 11, and near the lower edge of the furnace-front, on opposite sides of the opening 34, are openings 39 and 40, communicating by pipes 41 with the draft-passages 42, which communicate with the elbow-pipes of the side radiators.

43 designates a collar secured centrally to the upper end of the rear radiator for the attachment of a smoke-pipe.

30 44 and 45 designate, respectively, front and rear hollow walls, arranged within the lower section 4 of the casing and adjacent to the opposite sides thereof to form the side combustion ducts or passages 42. The front walls 35 44 are separated from the rear walls 45 by the vertical transverse end partitions or walls 46 and 47 of the hollow walls. The bottoms of the walls 44 are formed with air-inlets 48, and the rear hollow walls 45 are also provided with 40 air-inlets 49. The spaces 50 within the rear hollow walls 45 constitute the receiving-chambers for the air to be heated, and the air after being heated escapes to the hot-air-circulating pipes through openings 51, surrounded 45 by collars 52. The upper sides 53 of the hollow walls are oppositely beveled and formed with depending flanges 54, which engage or interlock with angle-brackets 55, secured to the inner sides of the casing.

50 56 and 57 designate angle-clamping plates fitting over the beveled upper ends of the hollow walls and extending inwardly beyond said walls to overlap the top edges of the fire-brick lining 58 of the fire-box 59. The inner 55 sides of the walls 44 and 45 are provided with flanges 60 to support the fire-brick lining 58 and grate 61. The clamping-plates 56 and 57 are formed with slots through which project loops or eyes 62, formed in the walls 44 and 60 45 and adapted to receive wedges 63 to secure the clamping-plate firmly in place.

64 designates a transverse wall located within the lower section of the shell or casing and separating the fire-box from the main combustion-chamber 65.

The spaces between the upper beveled edges of the hollow walls 44 and 45 and the

clamping-plates 56 and 57 form air-spaces 65 and 66 to permit air entering through perforations 67 of the hollow wall 44 to circulate 70 below the clamping-plate and pass through perforations 68 of the clamping-plates into the contents of the fire-box.

To the front side of the transverse wall 64 is secured by bolts 69 a flanged plate 70, the 75 lower end of which overlaps the rear lining of the fire-box.

The lower edge of each of the hollow walls 44 is secured by a groove or channel formed by oppositely-disposed angle-plates 71, secured to the bottom plate of the furnace.

The cross-wall 64 is formed on its rear side with vertical reinforcing-ribs 72 to impart rigidity and on its front side below the grate with vertical ribs 73 to support the fire-brick 85 and grate-rests at the bottom of the fire-box.

The union of the plate 70 with the cross-wall 64 forms a chamber 74 for the circulation of hot air entering through the ducts 67 and space 66 for the protection of the metal 90 and for discharge through perforations 75 over the fire or into the combustion-chamber to promote combustion of the gases which usually escape as waste products through the smoke-flues.

Within each of the side radiators 10 and 11 I arrange a vertical deflector-plate 76, said plate being located centrally between the ends of the radiators and serving to arrest and deflect the current of flame, &c., to secure a 100 more thorough diffusion thereof. The rear radiator is also provided with vertically-disposed parallel division-plates 77 to direct the incoming currents of heat and flame downward and then upward to the discharge-flue, 105 as illustrated by arrows in Fig. 7. The entrance to the rear radiator is controlled by a suitable damper 78.

In Figs. 8, 9, 10, and 11 I have shown a modified construction of the furnace, in which 110 is employed a smoke-chamber 79, located at the rear of the main combustion-chamber and firmly secured thereto. The front wall of the chamber 79 is provided with a removable shield comprising a metal plate 80, provided 115 at its upper side with a hook-flange 81, interlocking with a similar but oppositely-disposed flange 82, projecting from the casing of the chamber 79. The side radiators 10^a and 11^a communicate with the smoke box or 120 chamber 79, as shown at 83. The shield 80 protects the casing from undue heating, and the chamber 79 receives the dying products of combustion from the radiators and discharges them into the smoke-flue. The chamber 79 is provided with an opening 84, closed by 125 a damper 85, which permits the soot and ashes to be discharged to the bottom of the furnace for removal through the door provided for the purpose at the front of the furnace. The 130 damper also serves to provide a direct draft from the fire-box to the smoke-flue in starting the fire or when only a small amount of heat is required. The form of side radiators

and their connections to the furnace shell or casing shown in Fig. 9 affords a smaller and more compact structure than that shown in Figs. 1 to 7, inclusive.

5 I would have it understood that the invention is not restricted to all of the details of construction shown and described, but includes all such changes and modifications as may be made without departing from the scope of the invention as expressed in the following claims.

I claim—

1. In a hot-air furnace, a shell or casing comprising upper and lower sections detachably secured together the upper section being of rounded or dome shape, and the lower section being outwardly beveled; in combination with side and rear radiators, communicating with the casing by pipes entering the beveled portions of the lower section.

15 2. In a hot-air furnace, a shell or casing comprising sections detachably secured together, the lower section being outwardly beveled; in combination with vertical hollow walls, located within the beveled section of the casing to form therewith side ducts for the products of combustion; side radiators communicating with said side ducts; and a rear radiator communicating with the side radiators, and with the main combustion-chamber of the furnace.

3. In a hot-air furnace, the combination with a sectional shell or casing, of vertically-disposed hollow walls, forming with said shell side combustion-ducts; side radiators communicating with said combustion-ducts; and a rear radiator communicating with the side radiators and the shell or casing.

4. In a hot-air furnace, the combination with a shell or casing beveled outward at opposite sides, of horizontally-aligned hollow walls, having airinlets and outlets; side radiators communicating with the shell or casing and a rear radiator communicating with the side radiators and the shell or casing, the flue connections of said radiator joining the beveled portions of the casing.

45 5. In a hot-air furnace, the combination with a shell or casing, of hollow walls within

the casing located a sufficient distance from the sides thereof to form therewith ducts or passages; a fire-box between the hollow walls and clamping-plates detachably secured to the upper sides of the hollow walls for securing the lining of the fire-box.

55

6. In a hot-air furnace, the combination with a shell or casing beveled outwardly at opposite sides, of hollow walls arranged within the casing adjacent to the sides thereof to form therewith side passages for the products of combustion; side radiators communicating with said passages, and with the upper portion of the casing; a fire-box disposed between the hollow walls and clamping-plates arranged above the hollow walls and overlapping the lining of the fire-box.

60

7. In a hot-air furnace, the combination with the shell or casing, of hollow walls arranged adjacent to the sides of the casing, and secured thereto at their lower ends by flanged plates, and at their upper ends by interlocking flanges; clamping-plates detachably secured above the upper ends of the hollow walls with air-spaces between said plates and walls; and air-inlets in the walls and plates.

65

8. In a hot-air furnace, the combination with a shell or casing, of side radiators communicating with the casing, a smoke box or chamber within the upper portion of the shell or casing communicating with the upper portion of the side radiators; and a removable plate or shield for said smoke-box.

70

9. In a hot-air furnace, the combination with a shell or casing, of side radiators connected with the casing; a smoke box or chamber within the upper portion of the shell or casing communicating with the side radiators; a removable plate or shield for said smoke-box, and a damper at the bottom of said smoke-box.

75

90 In testimony whereof I affix my signature in presence of two witnesses.

PAUL W. BEECH.
